UNITED STATES PATENT OFFICE.

CHARLES WIEBKE, OF NEW YORK, N. Y.

WINDER.

No. 902,787.

Specification of Letters Patent.

Patented Nov. 3, 1908.

Application filed July 19, 1906. Serial No. 326,939.

To all whom it may concern:

Be it known that I, CHARLES WIEBKE, a citizen of the United States, residing at the borough of the Bronx, city of New York, in 5 the county of New York and State of New York, have invented certain new and useful Improvements in Winders, of which the following is a specification, reference being had therein to the accompanying drawings, forming 10 a part thereof.

My invention relates to machines for winding ribbons or other materials upon cards, thin boards or frames, and has for its objects, generally, simplicity and economy of construction, durability and strength, ease of manipulation and adjustment and a wide range of effective adjustment for cards or material holders of different thicknesses.

I will now describe the means embodying my invention illustrated in the accompanying drawings and will thereafter point out my invention in claims.

Figure 1 is a front elevation of the winder. Fig. 2 is an end elevation of the same. Fig. 25 3 is an enlarged detail, partly in section, of a pair of card-holding fingers and their holding and adjusting means.

The standard for holding the winder comprises a vertical rod 4 having at its lower end 30 a clamping member 5 provided with a clamping screw 6 whereby it may be clamped to the edge of a table or other suitable support. The vertical rod 4 at its lower end enters a bore in a boss 7 in the clamping member 6 and is held from rotation therein by a set-screw 8. The vertical rod 4 at its upper end enters a bore in a tee-shaped bearing block 9 and is held from rotation therein by a set-screw 10. The shaft 11 of the winder is 40 fitted to rotate in the bearing block 9 and is provided at one end with a hand-crank 12 and at the other end with a hub 13 for the winder arms 16, 17, this hub being held from rotation relatively to the shaft by a set-screw 14. 45 The hub 13 is provided with two parallel bores at right angles to the axis of the winder shaft 11, one bore for each winder arm, and the winder arms are separately adjustably held in their respective sockets in this hub by 50 set-screws 18, 18. Each winder arm has at its outer end fitted thereon and secured thereto by a set-screw 19 a finger-carrying member 20.

The card-gripping fingers for each winder 55 arm consist of two flat bars 21 and 22, secured to the finger-carrying member 20. One fin-

ger 22 is made slightly shorter than the other finger 21 to allow the card to be readily entered between the fingers. A card 29 is shown in Fig. 1 as held by the fingers in position for winding the ribbon thereon. The fingers are adjustable relatively to each other both to increase and diminish the space between them and to vary their relative inclination. This adjustability is accomplished by the provision of a plurality of adjusting screws whereby the fingers are held to a flat lug 26 of the finger-carrying member 20. The shorter finger 22 is shown as provided with a backing block 28, and two binding screws 24 and 25 are threaded into this backing block, but pass freely through the finger 22 and the finger 21 and the finger-carrying lug 26, their heads abutting against the outer face of the finger-carrying lug 26. 70 A clamping screw 23 passes freely through the finger-carrying lug 26 and is threaded into the finger 21 so that when tightened it clamps the finger 21 against the finger-carrying lug 26.

A spacing screw 27 is threaded into the backing block 28 and also into the finger 22 and abuts against the end of the clamping screw 23. This spacing screw 27 performs the function of clamping the finger 22 to the 80 backing block 28 by reason of the fact that it is threaded into both parts and that the threads are formed when the parts are tightly clamped together. It also performs the function of acting as an intermediate 85 spacing device and fulcrum. If, for example, it is desired to incline the fingers so that they will approach each other at their outer ends, the binding screw 25 is slackened and the binding screw 24 is tightened and the finger 22 will then turn on the end of the spacing screw 27 as a fulcrum as it moves to the desired position. If it is desired to cause the fingers to approach each other in parallelism, the spacing screw 27 is first slackened and 90 then the binding screws 24 and 25 equally tightened. At the final adjustment in any position the spacing screw 27 is so opposed to the binding screws 24 and 25 that it firmly 95 clamps the parts in the position to which they have been adjusted. It is desirable that the cards shall be so tightly gripped that they will not shift during the winding operation, but it is also desirable that they shall not be so tightly gripped as to prevent 100 their ready insertion and removal by an intentional act of the operator. This is ac-

complished in a satisfactory manner by the means above described, the spring of the fingers affording the required yielding grip after the fingers have been properly adjusted 5 for a card of the desired thickness. Further, the tendency due to the spring of the fingers to grip the cards less tightly toward the outer ends of the fingers may be counteracted by inclining the fingers towards each other, by 10 the adjusting means above described.

The winder is adjustable in every part, the manipulation of either one of the two screws 10 or 8 which hold the vertical rod 4, permitting the axis of the winder shaft to be 15 swung to any desired position in a plane at right angles to the vertical rod 4, and the clamping screws 18 permitting the respective winder arms to be separately adjusted to hold the fingers at desired distances from 20 the axis of the winder shaft, and the holding means for the fingers permitting the fingers to be adjusted both as to spacing and inclination.

In the operation of my winder, after 25 proper adjustment of the parts, the card is slid in between the blades and the end of the ribbon or yarn is properly secured and the winding operation performed by turning the hand-crank 12. When the ribbon has been 30 wound upon the card, the card with the ribbon thereon is withdrawn and is replaced by another card.

It is obvious that various modifications 35 may be made in the construction shown and above particularly described within the principle and scope of my invention.

What I claim as new and desire to secure by Letters Patent is:—

1. A winder comprising a single rotatable 40 frame having two pairs of diametrically arranged card-gripping fingers adapted to grip the cards at opposite ends thereof and rotate the cards end-over-end, and means for adjusting the fingers to grip cards of different 45 thicknesses.

2. A winder comprising a rotatable frame including a rotatable arm-carrying part and arms extending outward therefrom and ad-

justably held in separate sockets therein, and a pair of resilient card-gripping fingers carried by each arm and constructed and operating to grip the end of a card by their resilient action so as to rotate the card end-over-end. 50

3. A winder comprising a rotatable frame 55 having resilient card-gripping fingers extending therefrom and means for adjusting and fixing the inclination of the fingers relatively to each other.

4. A winder comprising a rotatable frame 60 having two pairs of card-gripping fingers extending therefrom and means for adjusting the inclination of the fingers of each pair relatively to each other and also adjusting said fingers bodily toward and from each 65 other.

5. A winder comprising a rotatable frame having card-gripping fingers extending therefrom and means for adjusting the fingers comprising a spacing screw located between 70 two binding screws.

6. A winder comprising a rotatable frame having a pair of resilient card-gripping fingers extending therefrom, one of such fingers being shorter than the other finger, and 75 means for adjusting the inclination of the fingers relatively to each other.

7. A winder comprising a rotatable frame having a pair of card-gripping fingers extending therefrom, one of such fingers being 80 shorter than the other finger, and means for adjusting the inclination of the fingers relatively to each other, and also adjusting the fingers bodily toward and from each other.

8. A winder comprising a rotatable frame 85 having a pair of card-gripping fingers extending therefrom, one of such fingers being shorter than the other finger, and means for adjusting the fingers comprising a spacing screw located between two binding screws. 90

In testimony whereof I have affixed my signature in presence of two witnesses.

CHARLES WIEBKE.
